[57] CLAIM

The ornamental design for a mask, as shown and described.

DESCRIPTION

FIG. 1 is a top and side perspective view of a mask showing my new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a left side elevational view thereof;

FIG. 7 is a right side elevational view thereof;

FIG. 8 is a top and side perspective view of a second embodiment of the mask; and,

FIG. 9 is a top and rear perspective view of FIG. 8. The bottom of the second embodiment being the same as the first embodiment shown in FIG. 3.

FIG. 1

FIG. 2

FIG. 3

FIG. 4

FIG. 5

FIG. 6

FIG. 7

FIG. 8

FIG. 9
